APPARATUS FOR TREATING HOLLOW BODIES

Joseph Gogan, Lakewood, Ohio

Application January 31, 1945, Serial No. 575,517

2 Claims. (Cl. 153—10)

1

This invention relates to apparatus for treating hollow metal bodies for trueing or straightening the same and for cooling or quenching such bodies when they are in a heated condition, and aims to provide improved apparatus for this purpose which is relatively simple and compact in construction and which carries out the desired operation in very effective and satisfactory manner.

Another object of the invention is to provide improved apparatus of this character, in which one or more groups of substantially radially movable segments form a die for applying pressure to the body being treated and in which novel means is employed for actuating the segments.

A further object of the present invention is to provide improved apparatus of this kind adapted to operate on a body while it is in a heated condition and in which provision is made for cooling the body by a flow of cooling medium while the body is held by the die.

Still another object of this invention is to provide improved apparatus for straightening or trueing a hollow body, such as an engine piston, by the use of groups of die segments adapted to apply pressure to the piston wall both internally and externally thereof and in which novel means is employed for actuating the groups of segments.

The invention can be further briefly summarized as consisting in certain novel combinations and arrangements of parts hereinafter described and particularly set out in the claims hereof.

In the accompanying sheets of drawings,

Fig. 1 is a front elevational view, with portions broken away, showing article treating apparatus embodying the present invention;

Fig. 2 is a side elevation of the same apparatus and with portions thereof broken away;

Fig. 3 is a partial plan view of the apparatus with the article therein shown in section;

Fig. 4 is a partial vertical sectional view of the apparatus taken on line 4—4 of Fig. 3;

Fig. 5 is a detail sectional view showing the connection between one of the pull rods and the segment actuating ring; and

Fig. 6 is another sectional detail view taken on line 6—6 of Fig. 4 and showing tongue and slot guiding means for the die segments.

The apparatus of the present invention can be used for the treatment of various hollow bodies but is especially useful in the heat treating and sizing of cylindrical hollow metal bodies such as engine pistons. The present embodiment of the apparatus is illustrated and described as being used for this purpose but it will be understood of course that this is not to be regarded as limiting

2

the scope of this invention to this particular use.

Before proceeding with the detailed description of the apparatus I will describe briefly the article or body being treated and which is here shown as an engine piston 10. The piston comprises a hollow body which includes the usual head 11 and cylindrical wall or sleeve 12. A wrist pin connection is provided internally of the piston in the form of an integral structure 13 depending from the head 11 and having a counterbore 14 to which further reference will later be made. The wall 12 is provided at axially spaced points with annular thickened portions 15 and 16 to which further reference will also be made hereinafter.

15 The embodiment of the apparatus shown in the drawings includes an upright frame or stand 18 having a substantially horizontal base plate or table 19 at the upper end thereof. The upper surface of this plate supports a die mechanism 20 which receives and operates upon individual pistons 10 as will be explained in detail hereinafter. The apparatus also includes a stationary upright hollow frame member or guide ring 21 in which the die mechanism 20 is located. The 25 lower end of the ring 21 is provided with a lateral flange 22 which seats on the plate 19 and is attached thereto by means of the screws 23.

The die mechanism 20 comprises inner and outer annular groups of elongated axially extending 30 die segments 24 and 25 which receive therebetween the cylindrical sleeve 12 of the piston 10. The segments 24 and 25 are provided in suitable number, and in this instance, each group comprises six segments. The segments 24 of the 35 inner group form an expandible die means which acts on the piston wall 12 interiorly thereof and the segments 25 of the outer group form a contractable die means which acts on the piston wall externally thereof.

40 The internal segments 24 engage the piston wall 12 at the thickened axially spaced annular portions 15 and 16 thereof and, for this purpose, each of the segments 24 is provided with corresponding axially spaced arcuate external portions 27 and 28. The arcuate portions 27 in aggregate form an annular pressure-applying means which is engageable with the inner periphery of the thickened portion 15 of the piston wall. Likewise, the arcuate portions 28 in aggregate 45 form an annular pressure-applying means which is engageable with the inner periphery of the thickened portion 16. The inner segments 24 also engage the piston 10 at a third point represented by the end and side faces of the counterbore 14. The upper ends of the segments 24 ex-

tend into this counterbore so as to form a means for locating and centering the piston in the die mechanism with the lower end of the piston wall 12 engaging or adjacent to the surface of the plate 19.

The outer segments 25 have arcuate work engaging surfaces 39 of a transverse curvature corresponding with the true curvature desired for the outer surface of the piston wall 12. The arcuate surfaces 39 of the outer segments in aggregate form a pressure-applying sleeve or cylinder which is engageable with the external surface or periphery of the wall 12 throughout the major portion of the length of the piston.

The piston 10 is placed in the die mechanism 20 by lowering the same into the sleeve or hollow die member defined by the outer group of segments 25 and with the open lower end of the piston telescoping over and around the die member formed by the inner group of segments 24. The head of the piston 10 may be provided with a suitable lifting ring or eye 31 for facilitating the operation of moving the piston into or out of the die mechanism.

The inner and outer die segments 24 and 25 are supported by the plate 19 and have their lower ends in sliding engagement with a flat bearing 32 which is recessed into the upper surface of this plate. During their expanding and contracting movements the die segments 24 and 25 are held in the desired annular arrangement and are guided for substantially radial movement by means of cooperating interfitting tongue and slot elements 33 and 34 provided respectively on the lower ends of the segments and on the flat bearing 32.

The inner group of segments 24 is expanded by means of an axially movable plunger 36 located inside of this group of segments and carried by an actuating rod 37 which is guided in a bushing 38 of the plate 19. The plunger 36 carries axially spaced upper and lower annular groups of substantially flat bearing faces 38 and 39 which are tapered or inclined relative to the axis of the die mechanism. These upper and lower groups of flat bearing faces 38 and 39 slidingly and wedgingly cooperate with corresponding spaced upper and lower annular groups of substantially flat bearing faces 40 and 41 provided on the segments 24 and which are also tapered or inclined relative to the axis of the die mechanism. The bearing faces 40 and 41 are preferably not formed directly on the segments 24 but on hardened inserts 42 and 43 which are mounted on the segments at axially spaced points and are attached to the segments by means of suitable screws 44.

As shown in Fig. 4 the tapers or inclinations provided for the substantially flat bearing faces 38 and 39 of the plunger 36 and the bearing faces 40 and 41 of the segments 24 are such that when the plunger is moved downwardly the groups of bearing faces 38 and 39 thereof will exert an outward wedging action against the bearing faces 40 and 41 of the segments 24 tending to expand the latter in the hollow body of the piston 10. This expansion of the segments 24 by the plunger 36 causes the portions 27 and 28 to apply expansive pressure to the inner peripheries of the thickened annular portions 15 and 16 of the piston wall.

Since the thickened portions 15 and 16 of the piston are spaced apart axially of the die mechanism it will be seen that engagement of the segments 24 with the work at these axially spaced points will cause the segments to be maintained in substantially parallel relation with each other.

during the application of pressure to the piston wall. The upper ends of the segments 24 apply expansive pressure to the annular side wall of the counterbore 14 which likewise assists in maintaining the segments in substantially parallel relation to each other.

The pressure which is applied internally to the wall 12 of the piston by the segments 24 in the manner just described opposes and cooperates with the pressure applied externally by the outer segments 25 and result in the piston being made to assume a true cylindrical shape. The pressure applied to the side wall of the counterbore 14 by the segments 24 acts to properly locate the structure 13 with respect to the axis of the piston. If the piston has been subjected to a previous heat treatment, as is usually the case, more or less warping or distortion may be present in the wall 12 and internal structure 13 and which distortion is removed by the straightening pressure applied by the segments 24 and 25. If the piston is placed in the die mechanism 20 while still in a heated condition, the pressure of the inner and outer segments 24 and 25 can be maintained during the cooling of the piston so that when it has been fully cooled it will have a true and accurate shape by reason of the fact that it has been held to the true shape by the applied pressure during the cooling operation.

The outer segments 25 are located in the stationary upright ring 21 but are spaced therefrom by an axially movable actuating ring or sleeve 46 which is disposed between this group of segments and an annular guide surface 47 formed by the inner wall or face of the stationary ring. The actuating ring 46 is provided at axially spaced points with upper and lower annular groups of substantially flat bearing surfaces 48 and 49 which are tapered or inclined relative to the axis of the die mechanism. The outer segments 25 are provided at corresponding axially spaced points with upper and lower annular groups of substantially flat bearing surfaces 50 and 51 which are also tapered or inclined relative to the axis of the die mechanism and with which the bearing surfaces 48 and 49 of the movable ring 46 slidingly and wedgingly cooperate. The bearing surfaces 48 and 49 are preferably formed on hardened inserts 52 and 53 which are secured to the ring 46 by means of appropriate screws 54. Likewise, the bearing surfaces 50 and 51 of the segments 25 are formed on hardened inserts 55 and 56 which are secured to the segments by means of appropriate screws 57.

The tapers of the annular groups of cooperating flat bearing surfaces 48 and 49 of the ring 46 and 50 and 51 of the segments 25 are such that downward movement of the ring will cause the segments 25 to be wedged inwardly or contracted so that their arcuate inner surfaces 30 will apply inward pressure to the outer periphery of the wall 12 of the piston. As indicated above, this pressure applied by the segments 25 opposes and cooperates with the pressure applied by the inner segments 24 and results in the wall of the piston being shaped and held to a true and accurate cylindrical form.

For actuating the inner and outer groups of segments 24 and 25 by the plunger 36 and the ring 46 respectively in the manner above described, the apparatus is provided with a suitable power device which is operably connected with the plunger and ring. In this instance the power device is in the form of a double-acting cylinder 60 which is located in the stand 18 and is con-

nected with the underside of the plate 19 by means of the open bracket 61. A piston 63 slideable in the cylinder is carried by an actuating rod 64 which projects from the lower end of the cylinder and is connected with a lower yoke 65. This lower yoke is connected, by means of a pair of spaced rods 66, with an upper yoke 67 which extends through the bracket 61.

The plunger 36 and the actuating ring 46 are both connected with the upper yoke 67. The lower end of the actuating ring 46 can be connected with the yoke 67 by means of spaced pairs of pull rods 68 whose upper ends extend through guide bushings 69 located in the plate 19 and are connected with the actuating ring as shown in Fig. 5. The actuating rod 37 of the plunger 36 has a shou'der 70 thereon which engages the upper side of the yoke 67 and a reduced stem 71 which extends through the yoke and carries a compression spring 72. The stem 71 and the spring 72 provide a yieldable actuating connection for the plunger 36 so that some relative actuating movement can take place between the plunger and the ring 46 during the straightening or sizing operation being performed on the piston 10. The spring 72 also provides means by which the pressures being applied by the inner and outer groups of segments 24 and 25 will be substantially equalized thus enabling both groups of segments to exert the full amount of pressure which they are intended to apply to the piston.

The cylinder 60 is provided with connections 74 and 75 adjacent its opposite ends and through which compressed air, or other suitable motive fluid, can be supplied. During the downward power stroke of the piston 63 the plunger 36 and actuating ring 46 are moved downwardly to thereby expand and contract the inner and outer groups of segments 24 and 25 respectively. During the upward power stroke of the piston the plunger and actuating ring are lifted so as to permit retraction of the inner and outer groups of segments relative to the workpiece 10. The segments 24 of the inner group are retracted by being moved toward each other as by means of the annular springs 76, 77 and 78 extending around these segments. The segments 25 of the outer group are retracted by being moved away from each other and outwardly relative to the workpiece 10.

For retracting the segments 25 of the outer group each segment is provided with a stud 80 which projects substantially radially outwardly therefrom so as to slidably extend through an opening 81 of the guide ring 21 and carries a compression spring 82. At points corresponding with the location of the studs 80 the actuating ring 46 is provided with axial slots 83 through which the studs extend and which permit axial shifting of the actuating ring. The springs 82 acting against nuts 84 provided on the outer ends of the studs 80 cause the segments 25 to be shifted outwardly or retracted when the actuating ring 46 is lifted.

As mentioned above, the piston 10 may be in a heated condition when it is placed in the die mechanism 20 and, as a part of the treatment given to the piston, it may be desirable to cool or quench the same while it is being subjected to the trueing or straightening pressure. To permit the circulation of cooling medium in or through the die mechanism, the outer segments 25 are preferably of a hollow construction so as to provide a cooling chamber 86 therein to which water or other appropriate cooling medium can

be supplied. The cooling medium can be supplied to the segments 25 through tubes or pipes 87 which are connected with the upper ends of the segments and communicate with the chamber 86. The lower ends of the segments 25 have openings or passages 88 therein which lead from the cooling chambers 86 and register with delivery openings 89 extending through the flat bearing 32 and the plate 19. The cooling medium supplied by the tubes 87 passes downwardly through the segments 25 and is discharged therefrom through the openings 89.

The cooling medium is also supplied to the piston 10 internally thereof and for this purpose the plunger 36 and the actuating rod 37 have an axial passage 90 therein and through which the cooling medium is supplied so as to be discharged or sprayed upwardly against the underside of the head of the piston. This sprayed cooling medium is spread or distributed laterally onto substantially all portions of the structure 13 and the inner surface of the wall 12. The cooling medium is supplied to the lower end of the passage 90 at a suitable point below the plate 19, as by means of the pipe connection 91. To permit the escape of the cooling medium from the interior of the piston, the annular portions 27 and 28 of the segments 24 are provided respectively with axially extending passages 92 and 93. Discharge openings 94 extending through the flat bearing 32 and the p'ate 19 receive the cooling medium from the passages 93 and permit it to flow freely out of the die mechanism.

As shown in Figs. 1 and 2, a suitable tank or hood 96 may be provided for collecting the cooling medium which is discharged from the die mechanism through the openings 89 and 94. The tank 96 is here shown as being of a size such that the apparatus can be located therein with the lower end of the stand 18 resting on the bottom of the tank.

From the foregoing description and the accompanying drawings it will now be readily understood that the present invention provides improved treating apparatus by which engine pistons, or various other hollow bodies, can be effectively subjected to trueing and straightening pressures and can also be cooled or quenched while such pressures are being maintained. It will be seen, moreover, that the present apparatus is simple and compact and acts in a positive and direct manner on the article being treated. It will be seen, moreover, that the die mechanism utilizes inner and outer groups of segments and is of a construction such that the pistons can be easily and quickly inserted into or removed from the mechanism.

While I have illustrated and described the improved article treating apparatus of this invention in considerable detail, it will be understood of course that the invention is not to be regarded as being correspondingly limited in scope but includes all changes and modifications coming within the spirit of the invention and the scope of the claims hereof.

Having thus described my invention, I claim:

1. In apparatus of the character described, a base plate, a guide ring fixed to said base plate on one side thereof with its axis extending substantially normal thereto, an annular group of segments defining a contractible hollow die located within and extending substantially coaxially of said guide ring, said segments being movable substantially radially of said guide ring and being slidably supported on said base plate, an ac-

tuating ring disposed between said segments and guide ring and being axially slidable in the latter, said actuating ring and segments having cooperating tapered thrust portions for causing contraction of the die in response to axial movement of the actuating ring, a power device located on the other side of said base plate, means extending through said base plate and operably connecting the power device with said actuating ring for transmitting thrust to the latter, the tapered thrust portions of said segments being spaced apart axially of the hollow die and being located adjacent the ends of the segments, and spring-actuated die-expanding means engaging said segments at a point between the tapered thrust portions thereof and acting on the segments to constantly hold their tapered thrust portions in engagement with the tapered thrust portions of said actuating ring.

2. In apparatus of the character described, a base plate, a guide ring fixed to said base plate on one side thereof with its axis extending substantially normal thereto, an annular group of segments defining a contractible hollow die located within and extending substantially coaxially of said guide ring, said segments being movable substantially radially of said guide ring and being slidably supported on said base plate, an actuating ring disposed between said segments and guide ring and being axially slidable in the latter, said actuating ring and segments having cooperating tapered thrust portions for causing contraction of the die in response to axial movement of the actuating ring, a power device located on the other side of said base plate, means extending through said base plate and operably con-

necting the power device with said actuating ring for transmitting thrust to the latter, said actuating ring having axial slots therein adjacent the respective die segments, rods connected with said segments and extending outwardly through said slots and through said guide ring, and segment retracting springs acting on said rods.
